(57) **CLAIM**

The ornamental design for a display box, as shown and described.

DESCRIPTION

FIG. 1 is a front perspective view of a display box showing my new design;

FIG. 2 is a front plan view thereof;

FIG. 3 is a rear plan view thereof;

FIG. 4 is a top plan view thereof;

FIG. 5 is a bottom plan view thereof;

FIG. 6 is a right side view thereof;

FIG. 7 is a left side view thereof; and,

FIG. 8 is a flat unfolded view thereof.

The broken lines showing the contents of the display box in FIG. 1 depict environmental structure only and form no part of the claimed design.

The dash-dot-dash lines in FIGS. 1 and 8 represent fold lines and form part of the claimed design.
